(57) CLAIM

The ornamental design for a seat, as shown and described.

DESCRIPTION

FIG. 1 is a perspective view of a chair showing my new design;

FIG. 2 is a left side perspective view thereof;

FIG. 3 is a front view thereof;

FIG. 4 is a rear view thereof;

FIG. 5 is a right side view thereof;

FIG. 6 is a top view thereof; and,

FIG. 7 is a bottom view thereof.

The fragmented crosshatching shown on the seat and backrest cushion is understood to represent fabric and would be continuous throughout the circumscribed areas.

1 Claim, 3 Drawing Sheets
